HERBERT H. STEELE, OF MARCELLUS, NEW YORK, ASSIGNOR, BY MESNE ASSIGNMENTS,
TO REMINGTON TYPEWRITER COMPANY, OF ILION, NEW YORK, A CORPORATION
OF NEW YORK.

COMBINED TYPE-WRITING AND COMPUTING MACHINE.

1,222,694.

Specification of Letters Patent.

Patented Apr. 17, 1917.

Application filed March 8, 1913. Serial No. 752,900.

To all whom it may concern:

Be it known that I, HERBERT H. STEELE, citizen of the United States, and resident of Marcellus, in the county of Onondaga and 5 State of New York, have invented certain new and useful Improvements in Combined Type-Writing and Computing Machines, of which the following is a specification.

My invention relates to combined type-writing and computing machines.

One object of my invention is to improve the connections between the carriage of the computer and the typewriter carriage, my improved connections being more especially 15 designed for an "open front" typewriter carriage. Said connections are, however, useful in connection with some other sorts of carriage than that specified.

Specifically stated, one of my objects has 20 been to connect up the Wahl computing mechanism with the Monarch typewriter. In carrying out this object, however, I have devised connections and combinations that are applicable or adaptable to machines 25 other than the Monarch and Wahl combination mentioned.

In the accompanying drawings,

Figure 1 is a side elevation, partly in fore and aft vertical section, of a machine embodying my invention, parts of the machine 30 being omitted.

Fig. 2 is a fragmentary transverse vertical sectional view showing some details of construction.

Fig. 3 is a front elevation of the machine 35 with some parts omitted.

Fig. 4 is a top plan view of the same.

Fig. 5 is a fragmentary front elevation 40 on a reduced scale showing a modification of or addition to the mechanism, designed for very wide or long carriages.

Fig. 6 is an enlarged fragmentary sectional view on the line $x-x$ of Fig. 5 and looking in the direction of the arrow at said 45 line.

Fig. 7 is an enlarged fragmentary view in fore and aft vertical section and showing some of the details of the ribbon connections.

Fig. 8 is a fragmentary front view of Fig. 7.

Fig. 9 is a left-hand side elevation of part of the mechanism.

The main frame of the Monarch type-

writer comprises a base part 1 from which 55 rise corner posts 2 that support a top plate 3. Standards 4 rise from said top plate and support stationary grooved carriage rails 5, which through anti-friction balls or rollers 6 support a carriage, which carriage consists principally of a back bar 7 grooved at its upper and lower edges to cooperate with the balls 6, and two end brackets 8 projecting forward from said back bar and having a roller platen 10 mounted therein. 65

The machine comprises a set of printing keys 11 arranged in four transverse rows. Most of these keys are omitted in the drawings which, however, show most of the back row of keys, these being the ones that print 70 the numerals from "0" to "9" inclusive. The keys 11 are mounted on the forward ends of key levers 12 which at their rear ends roll against a fulcrum plate 13, said key levers being held up against said plate by the returning springs 14. Upright sub-levers 15 are pivoted to said key levers at 16 and at their lower ends said sub-levers straddle a fulcrum bar 17. The upper ends of the sub-levers are connected by links 18 with type 80 bars 20 which type bars are pivoted in hangers 21 secured to a shiftable type bar segment 22. This segment is shiftable up and down for upper and lower case writing by means not shown but the segment is 85 guided at its two ends by posts 23 secured to the base 1 of the machine. Each of the type bars is provided with a restoring spring 24 and each of them has on its free end two types 25 one of which, in the case of 90 the type bars which are connected with the numeral key levers, is adapted to print one of the digits and the other type is adapted to print some other character.

The types 25 are adapted to strike against 95 the front face of the platen 10 around which the paper is fed by means which I have not thought it necessary to illustrate herein. The type, however, strike primarily against an ink ribbon 26 which is wound on two 100 spools 27, mounted on vertical shafts 28 (Fig. 4). Each of said shafts has thereon at its lower end a bevel gear 30 meshing with a bevel pinion 31 mounted on the forward end of a horizontal shaft 32 which 105 at its rear has a bevel gear 33 that meshes with a gear, not shown, on a drive shaft 34 that extends horizontally across the ma-

chine. Said drive shaft has thereon a bevel gear, not shown, which meshes with a bevel gear 35 mounted co-axially with the spring drum 36, which, through a band 37, drives 5 the typewriter carriage. The gear 35 is connected with said spring drum by a pawl 38 and ratchet 39. I have not shown all of the details of this ribbon drive as they are or may be of ordinary construction well 10 known in the art. In the Monarch machine the shaft 34 is usually made shiftable longitudinally to reverse the direction of the ribbon feed in a well known manner.

The ribbon is fed past the printing point 15 through a vibrator 40 consisting of a ribbon guide that can be slid vertically up and down on a guide 41 secured to the top plate 3. The vibrator 40 has a part thereof projecting below the top plate where it is pivotally connected with the forward end of 20 an operating lever 42 which at 43 is pivoted to a bracket 44 depending from the top plate 3. The lever 42 is of the first order and it is operated by means of a link 45 25 which has at its upper end a pin 46 projecting laterally therefrom into a slot 47 in the rear arm of the lever 42. The construction is such that the height to which the ribbon vibrator 40 is thrown can be varied 30 by moving the pin 46 in relatively close to the pivot 43, in which case the vibrator will be thrown to its greatest extent, and by adjusting said pin toward the rear end of 35 the slot as shown in Fig. 1, in which case the vibrator will be thrown upward to a less extent. The ribbon shown in the drawings and commonly used in connection with the computing machine, is made or inked in two stripes, having a lower stripe *a* of red 40 ink, for example, and an upper stripe *b* of a different color as black or blue. When the pin 46 is adjusted toward the forward end of the slot 47, the printing is from the lower stripe of the ribbon and when said 45 pin is adjusted as shown in Fig. 1, toward the rear end of the slot 47 the printing is from the upper stripe of the ribbon.

The lower end of the link 45 is pivoted to an arm 48 constituting part of a frame of 50 which a universal bar 50 is also a part, said universal bar lying beneath all of the key levers 12 and being pivoted at 51 in the base part of the machine.

The carriage feed is controlled by an escapement which I have not thought it necessary to illustrate herein as it is of well known construction. A feed rack pivotally mounted on the carriage engages a feed pinion which turns an escapement wheel that 60 cooperates with suitable dogs, which dogs are mounted on a dog rocker pivoted in the same bracket 52 that supports the spring drum 36; and said dog rocker is operated by a link 53 pivoted to the arm 48 above 65 mentioned.

The bi-color mechanism of the Monarch machine has not been fully illustrated herein, as it is of well known construction; but said mechanism is fully described and illustrated in the patent to Steele No. 1,009,351, 70 dated February 21st, 1911. Said mechanism comprises a sleeve 54 splined on the drive shaft 34 and controlled as to its position lengthwise of said shaft by an arm 55 which at its lower end is forked and enters a peripheral groove in the sleeve 54 and which at its upper end is secured to a transverse slide rod 56 having a pin 57 projecting upward therefrom into engagement with a bell crank 58 pivoted to the under side of the 80 top plate. Said bell crank is connected by a link 59 with a bell crank 60 pivoted to the under side of the top plate and having its forwardly extending arm formed into a handle 61. The construction is such that 85 by moving this handle toward the right the rod 56 and sleeve 54 are moved toward the right and by moving said handle toward the left said parts are also moved toward the left. In the Monarch machine the position of the sleeve 54 is controlled entirely by this handle but I have provided other connections between this mechanism and the computing mechanism, as will hereinafter appear. 95

The link 45 is drawn toward the rear of the machine by means of a spring 62, which spring keeps the said link constantly pressed into contact with the forward surface of the sleeve 54. This sleeve in the Monarch machine is usually made with three sections, one concentric section of small diameter with which the link 45 is shown in contact in Fig. 1, thus holding the link in its rear position to write from the upper 100 stripe of the ribbon; another section concentric with the shaft 34 but of larger diameter so that when the sleeve 54 is slid toward the left the link 45 engages this section of larger diameter and is moved toward the front thereby against the tension of its spring 62, thus moving the pin 46 105 nearer to the fulcrum 43 and increasing the extent of movement imparted to the vibrator, thus causing the writing to be done 110 from the lower stripe of the ribbon; and the sleeve 54 usually comprises also an eccentric section 63 shown by broken lines in Fig. 1, which, as the shaft 34 rotates, progressively changes the position of the link 120 45 and thus changes the extent of throw imparted to the ribbon. All of these details are brought out in the patent to Steele referred to and I have not deemed it necessary to illustrate them more fully herein. 125

The Monarch machine usually has a front cover plate 64 which is secured to the front posts 2 by means of screws 65. Pivoted to the back side of this cover plate at 66 is a plate 67 having at its upper end a notch 68 130

through which the forward arm of the bell crank 60 passes so that said bell crank and the plate 67 are constrained to move about their respective pivots in unison. The plate 5 67 has indicating marks 70 thereon which show through an opening 71 in the plate 64. Three of these marks 70 are here indicated and in the machine these are of such character as to indicate to the operator how the bi- 10 color mechanism is set. For example, one of these marks consists of a spot of blue, another of a spot of red and another has a sinuous line thereon to indicate the automatic cross feed setting of the mechanism.

15 The Wahl machine comprises an actuator 72 and a carriage 73 on which may be mounted one or more totalizers or adding heads 74. The actuator is supported and the carriage is supported in part by a frame 20 plate 75, the lower part of which extends the whole length of the actuator and constitutes the main frame piece thereof and the upper part of which has at the middle of the machine a number of rollers 76 mounted thereon 25 for coöperation with the carriage 73. One of these rollers lies beneath the carriage, another is above the carriage and another behind the carriage, and they all coöperate to control the carriage at the middle of the machine. 30 The precise construction of these parts is more or less immaterial so far as my invention is concerned, but the Wahl construction, or at least a suitable construction, is shown and described in the patent to Webster No. 35 968,103; dated August 23, 1910. The frame piece 75 is rigidly secured to the main frame of the typewriter by means of a bracket 77 which is secured to the upper surface of the top plate 3 by means of screws 78 and to 40 which the frame piece 75 is secured by bolts 79 (Fig. 3) having nuts 80 (Fig. 1) threaded thereon. The means for securing this frame piece 75 to the machine as shown in the present case, is more or less like that 45 heretofore employed in mounting the Wahl machine on the Remington typewriter. In the latter case, however, there are two separate brackets, one at each side of the machine, whereas in the present instance there 50 is a single bracket 77 which includes a connecting bar 81 extending across from one side of the machine to the other.

The Remington typewriter, on which the Wahl computer has usually been mounted 55 heretofore, has a carriage that extends near the front of the machine; that is to say, said carriage has a cross bar or rail near the front of the machine. The Monarch carriage is, on the contrary, of "open front" construc- 60 tion, not having any rail or substantial cross piece in front of the platen, and it is some little distance from the rigid framework of the Monarch carriage forward of the point where the computer carriage is situated. 65 The connection between the two carriages is

therefore made in the form of a truss in order to give the desired rigidity to said connection. Said truss or connecting frame includes two side bars 82, one at the right and the other at the left-hand ends of the carriages and extending forward from the typewriter carriage to the computer carriage. 70

In order to give these bars 82 the desired rigidity in an up and down direction, each of them is secured to the typewriter carriage 75 at two points. The platen 10 has a shaft 83 (Figs. 1 and 2), which shaft is journaled in sleeves 84 inserted through suitable openings in the end brackets 8 of the carriage, where said sleeves are secured in place by set 80 screws 85. Each of these sleeves is formed long enough to project a suitable distance outside of the bracket 8 and, at least on the left-hand side, the bracket or bar 82 is formed or provided with a hub 86 which surrounds this projecting sleeve 84.

The Monarch carriage comprises a transverse frame rod 87 mounted above the platen and connected at its ends to ears 88 projecting upward from the brackets 8. A screw 90 passes through each of these ears 88 and is threaded into the end of the rod 87, drawing said rod tightly against the inner face of the ear. The bar 82 at the right-hand end of the carriage is, as shown in Fig. 4, secured by 95 this screw 90 to the outside face of the ear. In other words, the bar 82 is formed with a suitable hole through which the screw 90 passes so that said screw not only holds the frame bar 87 in place but also holds the bar 100 82 in place. This bar is therefore connected at two places, namely, at the sleeve 84 and at the screw 90, thus giving it a rigid mounting on the bracket 8.

The left-hand screw 90 in the Monarch 105 machine usually supports not only the bar 87 but also outside of the ear 88 said screw passes through and supports a nut-like washer 91 having a reduced part on which is pivoted a link 92 constituting part of the 110 paper feed release mechanism. The left-hand bar 82 is mounted on the screw 90 outside of this collar or washer 91 and it is partly for this reason, namely, that this bar is spaced away from the bracket 8 by the 115 paper feed mechanism, that the left-hand one of the bars 82 is provided with a hub 86 to space it away from the sleeve 84 correspondingly.

Throughout the greater part of its length 120 each of the brackets 82 is made of angled cross section, as will be understood from the drawing. Each of these bars thus comprises a vertically disposed part and a horizontally disposed part, the former of which is 125 secured to the typewriter carriage, as has been described, and the latter of which at its forward end is prolonged and bent into an arm 93 which is connected with the computer carriage. Preferably this arm is bent, 130

as shown in Fig. 1, first upward, thence toward the front of the machine and thence downward, so that each of these arms 93 has a vertically disposed ear 94 that lies just back of a plate 95, which projects outward from the end of the carriage 73 to which said plate is secured by screws 96. Plates of the same general character as these plates 95 are employed in the Wahl machine as mounted on the Remington typewriter, and each of them has a vertically elongated slot 97 therein through which passes a screw 98 threaded into the ear 94 and secured by a lock nut 99, Fig. 1. The slot 97 and screw 98 are so related in size and disposition that the carriage 73 is substantially held against motion toward the right and left relative to the ears 94 but each end of the carriage has a certain amount of freedom of motion with relation to said ears in an up and down direction. All of this is fully explained in the patent to Webster referred to.

The double bend in the arm 93, or the angular formation of said arm, as shown in Fig. 1, enables a suitable adjustment to be made of the ears 94, both in a front and back direction and also if necessary in an up and down direction by appropriately bending said arm 93, as will be readily understood.

The truss connection between the two carriages also comprises a transverse bar 100 situated in front of the platen 10, as shown in Fig. 4. This bar passes through suitable holes at the forward ends of the vertical webs of the bars 82 and constitutes the front cross bar of the truss frame which connects the typewriter and computer carriages. In order to give the necessary rigidity to the frame, said frame includes truss elements which, while they may be variously constructed, are here shown as consisting of one or more oblique bars or braces. In the present instance there are in effect two of these bars but made of a single rod 101 which at its middle part is rigidly secured as by rivets 102 to the bar 100. The two ends of the bar 101 extend backward and outward obliquely so as to serve as braces and each of them passes through a suitable hole in the vertical web of one of the bars 82 a comparatively short distance in front of the platen. Both of the bars 100 and 101 are threaded at each of their ends and nuts 103 are threaded on to said bars, at least two nuts on each end of each bar, one of said nuts being inside and the other outside of the bar 82. The whole construction is such that various adjustments can be made by changing the nuts 103. In assembling the machine all of these nuts are adjusted in such a way as to space the two screws 98 apart a distance equal to the spacing of the two slots 97.

It is essential, when the typewriter and computer carriages are standing still at

some point in an adding zone, that the computer carriage be positioned with some nicety in a right and left-hand direction in order that the master wheel may engage exactly with the appropriate register wheel 70 and also in order that some of the other parts may coöperate properly and with certainty. A relative adjustment between the typewriter and computer carriages, sufficient to insure the proper position of the 75 computer carriage, can be effected by changing the adjustment of the nuts 103 that are threaded on to the bar 100, leaving the nuts on the bar 101 in the position they had at the end of the first adjustment. Leaving 80 these latter nuts undisturbed preserves the proper spacing between the two arms 82, and shifting all of the nuts 103 one way or the other on the bar 100 will change slightly the angle which each of said bars will make 85 with relation to the other parts of the machine, as for example any line which represents the direction of travel of the carriages. The forward ends of the two bars 82 will thus be thrown a little to the right or a little 90 to the left with relation to the typewriter carriage, thus bringing it about that when said carriage stands at an exact letter space position, the computer carriage is also with sufficient exactness situated in one of its operating 95 positions.

The line space mechanism of the typewriter includes a line space ratchet wheel 104 which is engaged by a pawl 105, which pawl is operated in a manner that need not 100 be here precisely described by the rocking of a shaft 106. This shaft extends in a front and back direction through and above the left-hand carriage bracket 8, being journaled at its rear end in an ear 107 of said 105 bracket (Figs. 1 and 4). The forward part of said shaft is journaled in a sleeve 108 (Fig. 2) which passes through the bracket 8 and has an arm 110 (Fig. 1) mounted thereon and depending therefrom, said arm having a hub 111 at its lower end with a puppet 112 extending through it and projecting into one of three suitable holes 110 in the front face of the bracket 8. This arm and puppet or lock are moved in a right 115 and left-hand direction and located in one or another of said holes, thus rocking an arm 113 which has a bearing on the rear end of the sleeve 108, and the rocking of which arm makes a difference in the extent 120 of feed imparted to the platen at each actuation of the pawl 105. The parts are provided with a restoring spring 114 (Fig. 1) and with a handle which is secured to the forward end of the shaft 106. All of this 125 mechanism is well known in the art and a description of it will be found in the patent to Merritt, No. 791,483, dated June 6, 1905. I prefer to prolong the shaft 106 considerably 130 farther toward the front of the ma-

chine than the regular Monarch construction. To this end I have shown mounted on the forward end of the shaft 106 a collar 115 which is secured to said shaft by a pin 116, said collar occupying about the position ordinarily occupied by the hub of the line space handle or lever. A shaft 117 is secured in said collar by a pin 118 and said shaft has the line space handle 120 mounted on its forward end and projecting upward after the fashion of the ordinary Monarch line space lever. The forward end of the shaft 117 is journaled in a bracket 121 secured by screws 122 to the inner face of the left-hand bar 82. By the described means the handle is situated nearer the front of the machine which is a better location for it when the computing mechanism is mounted on the machine, as shown, as the operator has to reach over said mechanism in order to work this handle or lever.

The adding heads 74 and actuator 72 are of the ordinary Wahl construction, the latter including a master wheel 123 that meshes with wheels 124 constituting part of the registering mechanism. Said master wheel is operated by differential mechanism including a graduated set of arms 125 which are operated by certain cams, which cams are controlled by levers 126, which levers are operated by links 127, the lower ends of which are connected to the several key levers 12 for the numerals or digits. These connections are or may be of substantially the same general character as those heretofore employed in connection with the Wahl machine.

The Wahl machine includes means for changing the connections between the arms 125 and the master wheel 123 so as to turn said master wheel one way for addition and another way for subtraction. Said means include change gear mechanism, part of which is shown in Fig. 4 at 128, and said change gear mechanism is operated by a slide rod 130, which is supported at one end in the actuator and near its left-hand end in an ear 131 projecting from the framework of the actuator. At its left-hand end the rod 130 has a pin or screw 132 projecting through it into a cam slot 133 formed in a convex or arc-shaped plate 134, which plate projects from a sector or lever arm 135 pivoted at 136 to the left-hand end of the actuator. The cam slot 133 includes a middle cam portion and two dwells, one at each end, and it is of such form that when the plate 134 occupies its rear position shown in the drawings the rod 130 is in its right-hand position and the change gear mechanism is set for addition, whereas when the lever 135 is rocked toward the front of the machine the rod 130 is moved toward the left and the change gear mechanism is set for subtraction. The lever 135 has its mo-

tion limited by a screw 137 passing through a slot 138 in said lever arm and threaded into the end of the actuator. Said lever arm is operated by a key or handle 140 projecting from the forward end of a lever arm 141 which is secured adjustably to the lever arm 135. Said lever arm 135 is held in its normal position, shown in the drawings, by means of a restoring spring 142 connected at one end to a fixed part and at the other end to an arm 143 of the lever 135. This spring normally holds the parts in position for addition and restores them to that position after the key 140 has been depressed and released. The parts can be held in subtracting position, however, against the tension of said spring by means of a latch 144. The mechanism just described is the ordinary add-and-subtract change mechanism of the Wahl machine.

It is customary in using a combined typewriter and adding machine to write the added numbers in an ordinary color as blue or black and to write subtracted numbers, including totals, in a distinctive color as red. It will, of course, be understood that the add-and-subtract mechanism can be shifted by hand and the bi-color mechanism of the typewriter which has been described can be shifted at the same time in harmony with the setting of the computing mechanism from one character of operation to the other. I prefer, however, to provide an automatic connection between these two parts so that if desired the shifting of one of them will automatically shift the other in harmony therewith. Such a connection has been provided heretofore between the add-and-subtract mechanism of the Wahl machine and the bi-color mechanism of the Remington typewriter on which said machine has been mounted. I therefore prefer to make my connections between the add-and-subtract mechanism of the Wahl machine and the bi-color of the Monarch machine of such character as to imitate in a way the like mechanism in the Wahl-Remington combination so that operators who have been accustomed to the Wahl-Remington combination will have no new operations to learn in using the Wahl-Monarch combination; and vice versa.

The connections from the Wahl add-and-subtract mechanism to the bi-color mechanism of the typewriter, comprise a link 145 (Figs. 3 and 9) which at its upper end is pivoted to the lever arm 143 and at its lower end is pivoted at 146 (Figs. 3 and 8) to the horizontal arm of a lever 147, which lever is pivoted on a rock shaft 148 that projects through the cover plate 64 near the left-hand front post 2 and which at its rear end takes a bearing in a suitable hole in the post 23 which guides the shiftable segment 22. The construction is such that when the

key 140 moves upward the link 145 moves downward, and vice versa, so that the lower position of said link and of the lever arm 147 corresponds to the addition position of the computing mechanism. The lever 147 has an upwardly projecting arm 150 which is shaped to serve as a pointer to indicate the position of the parts and if desired a suitable indicator can be mounted or formed on the front face of the plate 64 to co-operate with this pointer and with another pointer 151 (Fig. 7) that normally stands just in front of the pointer 150. This second pointer 151 is fixed on the hub of a button or milled head 152 which is loosely mounted on a sleeve 153 surrounding the front end of the shaft 148 and secured in position thereon by means of a screw 154 threaded into the forward end of said shaft. The sleeve 153 is a spacing sleeve which at its forward end bears against the broad head of the screw 154 and at its rear end against the lever 147, which lever lies against the front face of the plate 64. It will be seen that the lever 147, sleeve 153 and screw 154 prevent motion of the shaft 148 toward the rear. The motion of said shaft toward the front is prevented by a collar or sleeve 155 which surrounds said shaft just back of said cover plate and is secured to the shaft by any suitable means as, for example, by a set screw. The pointer 151 constitutes the upper part of a plate-like device which at its lower part is bent toward the rear, constituting an arm 156 that extends through an arc-shaped slot 157 (Figs. 7 and 8) in the plate 64 and at its rear end is bent into a V-shaped detent 158 which co-operates with a flange 160 turned on the rear end of the sleeve 155. The button 152 and plate or pointer 151 can be slid forward or backward and these parts will be yieldingly retained in either of their two positions by the detent 158. The motion of said parts is permitted and limited by an annular enlargement 161 in the front end of the hole through which the sleeve 153 passes. The rear end of said enlargement constitutes a shoulder co-operating with the head of the screw 154 to limit the outward motion of the button and its connected parts. The right-hand part of the plate 151 is formed as shown in Fig. 8 of a sector shape having therein a notch 162 into which a pin 163 is adapted to project from the lever 147. The construction is such that when the button 152 is in its rear position, shown in Fig. 7, the pin 163 engages the notch 162 and constrains the plate 151 and the lever 147 to turn together, whereas when the button 152 is pulled forward these two parts can turn independently of each other. When the button is thus pulled out the add-and-subtract mechanism of the computer and the bi-color mechanism of the typewriter are disconnected from each other and when the button is pushed in these parts are connected up to operate automatically in unison. The connections from the plate 151 to the bi-color mechanism include a plate or lever 164 mounted on the reduced forward end of the sleeve 155 and having in its lower end a notch 165 through which the arm 156 passes, and so that whenever the button 152 and plate 151 are turned about the axis of the shaft 148, this arm 164 is turned with said button and plate whether the button and plate are in their forward or in their rear position. Above the shaft 148 the arm 164 has pivoted thereto at 166 a long link 167 that extends across the machine back of the plate 64 and is pivoted at 168 to the plate 67 of the bi-color mechanism. Through this link the button 152 and plate 151 and the bi-color mechanism of the machine are always set in harmony and when said button is in its rear position the bi-color of the typewriter and the add-and-subtract mechanism of the computer are connected together.

The button 152, plate 151, lever 147 and shaft 148 are all substantially like parts in the Remington typewriter by means of which the bi-color mechanism of that typewriter is controlled, and these parts are connected up with the computer and disconnected therefrom in exactly the same way in the present construction as in the Wahl Remington combination.

It will be noted that the rollers 76 support the computer carriage only at the middle of the typewriter and that when the typewriter and computer carriages are in their extreme right-hand or left-hand positions, much of the weight of the computer carriage comes on the connections to the typewriter carriage. This weight is not too much for the typewriter carriage to bear, provided the carriages are not too long. In some cases, however, the carriages of these machines are made of considerably more than the ordinary length and in such a case the weight of the computer carriage that would have to be borne by one or the other of the bars 82 would be quite considerable, and this weight would be more objectionable in an "open front" carriage than it would in a carriage that had a rail near the front of the machine. In order to relieve the typewriter carriage of this extra weight in the case of very wide or long carriages, I may add to the devices already described such an additional carriage support as is shown in Figs. 5 and 6. In these figures I have provided at a suitable distance at one side of the typewriting machine a supporting roller or wheel 170 which as here shown is journaled on a stud bolt 171 having a flange 172 and passing through an up and down slot in a bracket 173 where said stud bolt is secured by means

of a nut 174. An additional wheel of this character is mounted on each side of the typewriter, only one of them being shown here as they both are or may be substantially alike. The wheels 170 may be supported in any suitable manner but as here shown a bracket 173 is riveted to and projects forward from a truss member or bracket 175 which, as shown in the present instance, is made of ribbon metal bent into the form shown and comprising a horizontal arm that is secured to the top plate 3 of the typewriter in any suitable manner and of an oblique arm 176 that is secured to the lower part of the typewriter frame. As here shown, the horizontal arm of this brace or truss is supported by the screw 78 and also by the screw 177 which connects the top plate 3 with the post 2, this screw being made a little longer than usual for the purpose. The oblique arm 176 of the truss is here shown fastened to the side of the post 2 by means of a screw 178. Preferably the rollers 170 are at such positions at the right and left-hand sides of the machine that when the carriage 73 stands in its middle position both rollers are beneath said carriage and preferably when said carriage stands in said middle position and is exactly balanced on the rollers 76, the two rollers 170 would be slightly lower than the lower edge of said carriage. This is to insure that the carriage runs easily on to the rollers when it reaches them. It will be recalled that the ends of the carriage have a certain amount of freedom of motion up and down, due to the character of their connections with the bars 82.

Various changes can be made in the details of construction and arrangement without departing from my invention.

What I claim as new and desire to secure by Letters Patent, is:—

1. In a combined typewriting and computing machine, the combination with a typewriter carriage and a computer carriage, of an intermediate frame connecting said carriages and including a transverse front bar, two side bars, each connected at its rear end to said typewriter carriage, and at its forward portion to one end of said front bar, and oblique braces connected to said front bar and also connected at their outer ends to the side bars of said intermediate frame.

2. In a combined typewriting and computing machine, the combination with a typewriter carriage and a computer carriage, of a truss connecting said carriages, said truss having means for affording a relative adjustment between its members and thereby a relative adjustment of the two carriages.

3. In a combined typewriting and computing machine, the combination with a

typewriter carriage and a computer carriage, of a truss connecting said carriages and comprising end bars, a cross bar, and one or more oblique bars, and means for effecting relative adjustment between said cross and oblique bars and said end bars.

4. In a combined typewriting and computing machine, the combination with a typewriter carriage and a computer carriage, of end bars rigidly connected to said computer carriage, a cross bar rigidly connecting said end bars near said computer carriage, and one or more oblique bars, said bars having provision for relative adjustment to regulate the distance apart of the free ends of said end bars and the angles of said end bars with the line of carriage travel.

5. In a combined typewriting and computing machine, the combination with a typewriter carriage and a computer carriage, of end bars connected to the typewriter carriage so as to be rigid in an up and down direction, connections between said arms and said computer carriage such as to allow to said computer carriage at the points of connection a limited motion up and down, means for supporting said computer carriage between said arms, and adjustable truss connections between said arms to regulate the positions in a right and left-hand direction of the ends of said arms at said computer carriage.

6. In a combined typewriting and computing machine, the combination of a typewriter carriage, a computer carriage, and connections between said carriages, said connections including end bars secured to said typewriter carriage and extending forward therefrom and each of said end bars having therein near its forward end a double bend by bending which an adjustment can be effected to regulate the effective length of said arm.

7. In a combined typewriting and computing machine, the combination of a typewriter carriage, a computer carriage, and connections between said carriages including two end bars secured to the typewriter carriage and each made of sheet metal folded through part of its length to make a rigid angle bar having a horizontal part and a vertical part and said horizontal part being prolonged beyond the vertical part and having a double bend therein for the purpose of adjustment.

8. In a combined typewriting and computing machine, the combination of a typewriter carriage, a computer carriage, and connections between said carriages including two end bars secured to the typewriter carriage and each made of sheet metal folded through part of its length to make a rigid angle bar having a horizontal part and a vertical part and said horizontal part being prolonged beyond the vertical part and having a double

- bend therein for the purpose of adjustment, and said vertical parts of the two end bars being connected by one or more cross bars.
9. In a combined typewriting and computing machine, the combination of a typewriter carriage, a computer carriage, and connections between said carriages including two end bars secured to the typewriter carriage and each made of sheet metal folded through part of its length to make a rigid angle bar having a horizontal part and a vertical part and said horizontal part being prolonged beyond the vertical part and having a double bend therein for the purpose of adjustment, and said vertical parts of the two end bars being connected by one or more cross bars, said cross bars and end bars constituting a truss.
10. In a combined typewriting and computing machine, the combination of a typewriter carriage, a computer carriage, and connections between said carriages including two end bars secured to the typewriter carriage and each made of sheet metal folded through part of its length to make a rigid angle bar having a horizontal part and a vertical part and said horizontal part being prolonged beyond the vertical part and having a double bend therein for the purpose of adjustment, and said vertical parts of the two end bars being connected by one or more cross bars, said cross bars and end bars constituting a truss.
11. In a combined typewriting and computing machine, the combination with a typewriter carriage and a computer carriage, of a frame connecting said carriages and including two end bars, a cross bar connecting said end bars near their forward ends and braces connected with said end bars at points remote from the points of connection in rear of said cross bar to said end bars, and said braces being also connected with said cross bar.
12. The combination with a carriage carrying a platen and provided with a forwardly extended frame consisting of elongated side bars, a front bar, and diagonally arranged bars between the front bar and the platen, the diagonal bars being attached to the front bar between its ends, and the outer ends of the diagonal bars and of the front bar being secured to the side bars at distant points whereby the side bars are rigidly connected together at four different points, and a computer carriage loosely connected to the front portion of said forwardly extended frame.
13. In a combined typewriting and computing machine, the combination with a typewriter carriage and a computer carriage situated in front of said typewriter carriage and at a distance therefrom; of a connecting frame comprising two side arms lying in a front and back direction and connected to said typewriter carriage, a cross bar located between the two said carriages and connecting said side arms, diagonal braces in the angles between said cross bar and said side arms, and extensions projecting forward from the location of said cross bar, each of said extensions connected with the said computer carriage.
14. In a combined typewriting and computing machine, the combination with a typewriter carriage and a computer carriage situated in front of said typewriter carriage and at a distance therefrom; of a connecting frame comprising two side arms lying in a front and back direction and connected to said typewriter carriage, a cross bar located between the two said carriages and connecting said side arms, and extensions projecting forward from the location of said cross bar, each of said extensions connected with the said computer.
15. In a combined typewriting and computing machine, the combination with a typewriter carriage and a computer carriage situated in front of said typewriter carriage and at a distance therefrom; of a connecting frame comprising two side arms lying in a front and back direction and connected to said typewriter carriage, a cross bar located between the two said carriages and connecting said side arms, and extensions projecting forward from the location of said cross bar, each of said extensions connected with the said computer carriage.
16. In a combined typewriting and computing machine, the combination with a typewriter carriage and a computer carriage situated in front of said typewriter carriage and at a distance therefrom; of a connecting frame comprising two side arms lying in a front and back direction and connected to said typewriter carriage, a cross bar located between the two said carriages and connecting said side arms, diagonal braces in the angles between said cross bar and said side arms, and extensions projecting forward from the location of said cross bar, each of said extensions connected with the said computer carriage.
